UNITED STATES PATENT OFFICE

156,318

DIRECTION SIGNAL FOR VEHICLES

Irving E. Brown, Newark, N. J.

Application July 30, 1948, Serial No. 147,854

Term of patent 14 years

(Cl. D72—1)

To all whom it may concern:

Be it known that I, Irving E. Brown, a citizen of the United States of America, residing at Newark, in the county of Essex and State of New Jersey, have invented a new, original, and ornamental Design for Direction Signal for Vehicles, of which the following is a specification, reference being had to the accompanying drawing, forming part thereof.

In the drawing,

Fig. 1 is a top plan view of a direction signal for vehicles, embodying my new design,

Fig. 2 is a front elevational view of same.

Fig. 3 is a bottom plan view of same, and

Fig. 4 is an end elevation of same, looking at the right-hand end as shown in Fig. 2.

The dominant characteristics of the design reside in those portions shown in full lines in the drawing.

I claim:

The ornamental design for a direction signal for vehicles, as shown and described.

IRVING E. BROWN.
